UNITED STATES PATENT OFFICE.

BENJAMIN C. BROWNELL, OF CENTRE JUNCTION, IOWA.

SELF-CLEARING BREAKING-PLOW COLTER.

SPECIFICATION forming part of Letters Patent No. 340,281, dated April 20, 1886.

Application filed September 4, 1885. Serial No. 176,131. (No model.)

To all whom it may concern:

Be it known that I, BENJAMIN CRANDALL BROWNELL, of Centre Junction, in the county of Jones and State of Iowa, have invented a new and Improved Self-Clearing Breaking-Plow Colter, of which the following is a full, clear, and exact description.

My invention relates to improvements in plow-colters; and it consists in the peculiar construction and arrangement of parts, as hereinafter fully described, and pointed out in the claims.

Reference is to be had to the accompanying drawings, forming a part of this specification, in which similar letters of reference indicate corresponding parts in all the figures.

Figure 1 is a side view of a breaking-plow with my colter-clearing attachment applied thereto. Fig. 2 is a plan view of the same; 20 and Fig. 3 is a view similar to Fig. 1, except that the clearing-roller is shown in section.

A represents the beam, B B the handles, and A' the mold-board, of the plow. The colter-standard C is secured to the beam A in the ordinary manner, and at its lower end is welded to the colter D. A spindle-like roller, E, formed with an outwardly-flaring top, a, is mounted on a rod, b, the lower end of which rides in a socket formed in the upper part of the colter D, the top of the rod being carried backward and held in place by the strip c, which is held against the beam A by the clips d d, so that the roller E is mounted at an angle which is a practical continuation of that given to the colter D. The lower end of the roller E is protected by a shield, F, which is firmly riveted to the colter D.

In order that the roller may be moved to 40 or from the colter, the bar b is threaded and carries two adjusting-nuts, i i, which also serve as washers and define the position of the roller upon the bar, being moved up or down, as the circumstances of the case require.

When the plow to which my self-clearing attachment is secured is in operation, any hazel-brush, weeds, grass, or other obstructing material caught by the colter will, on account of the incline given thereto, rise above the colter and shield F until it rests 50 upon the roller E, a further rise being prevented by the flaring top a. After the obstructing material has risen so as to rest against the roller E, it is likely to be caught upon one side or the other, and when so caught a 55 very slight pull will cause the roller to revolve and discharge itself.

Having thus described my invention, what I claim as new, and desire to secure by Letters Patent, is—

1. The combination, with a colter, of a bar held above the same, and a vertically-adjustable roller thereon, substantially as described.

2. The combination, with a plow-beam, a standard secured thereto, and a colter on the lower end of said standard, of a bar secured to the beam and colter in an inclined position in front of the colter-standard, and a vertically-adjustable roller on said bar, substantially as herein shown and described.

3. The combination, with a plow-beam and colter, of a threaded rod secured to the beam and colter, a roller on said rod, and nuts above and below the roller, for adjustably securing the same on the rod, substantially as 75 herein shown and described.

4. The combination, with the beam A, the standard C, and the colter D, provided with the shield F, of the threaded rod b, the roller E, the nuts i, the plate c, and clips d, substantially as herein shown and described.

BENJAMIN C. BROWNELL.
